ROTARY LAWN SPRINKLER

Jean O. Reinecke, Pasadena, Calif., assignor to Rain
Bird Sprinkler Mfg. Co., Glendora, Calif.

Filed May 3, 1973, Ser. No. 357,033

Term of patent 14 years

Int. Cl. D23—01

U.S. Cl. D23—7

FIG. 1 is a perspective view of a rotary lawn sprinkler embodying my new design;

FIG. 2 is a side elevational view thereof;

FIG. 3 is another side elevational view thereof; and
FIG. 4 is a top plan view thereof.

I claim:

The ornamental design for a rotary lawn sprinkler, substantially as shown.
